Inventor Elijah G. Cate,

By Attorney George H. Christy.

UNITED STATES PATENT OFFICE.

ELIJAH G. CATE, OF BRIDGEPORT, OHIO, ASSIGNOR TO LA BELLE GLASS COMPANY, OF SAME PLACE.

DESIGN FOR INKSTANDS.

Specification forming part of Design No. 9,718, dated January 23, 1877; application filed November 11, 1876.
[Term of Patent 7 years.]

To all whom it may concern:

Be it known that I, ELIJAH G. CATE, of Bridgeport, county of Belmont, State of Ohio, have invented or discovered a new and useful Design for Inkstands; and I do hereby declare the following to be a full, clear, concise, and exact description thereof, reference being had to the accompanying drawing, making a part of this specification, in which—like letters indicating like parts—

Figure 1 is a perspective view of an inkstand illustrative of my improved design. Fig. 2 shows a vertical cross-section midway between its ends, and Fig. 3 shows a longitudinal vertical section through the ink-wells.

My improved design relates more particularly to the relative arrangement or grouping together in and on a single base of ink wells, cups, and covers, sand or pen holder, and sponge-cup acting as a cover.

The base A is of any desired exterior shape, with or without the pen and pencil racks A'. In the upper face of the base A are four depressions or wells, a a c e, of which the two end ones, a a, are nearly or exactly coun-

terparts of each other. In these two wells are the ink-cups a¹ a¹, provided with stoppers or covers a² a², made also of similar shape and general appearance. Between these two is a third well, c, also occupied by a cup, c¹, covered by a cover or stopper, c², shaped and ornamented as may be desired. In the rear of this central well and cup is the fourth well, e, covered by a combined cup and cover, e¹.

This grouping of the parts designated in and on a single base, aside from utility, gives an article having an appearance pleasing, symmetrical, and, when in use on a writing desk or table, highly ornamental.

I claim herein—

The design, in an inkstand, of wells, cups, and covers or stoppers, relatively grouped in and on a common base, substantially as described and shown.

In testimony whereof I have hereunto set my hand.

ELIJAH G. CATE.
